UNITED STATES PATENT OFFICE.

ERWIN E. MILLER, OF FULLERTON, CALIFORNIA.

VALVE GRINDER.

Application filed November 16, 1923. Serial No. 675,079.

This invention relates to valve grinders and has for an object to provide a tool of portable character that is adapted to be readily attached directly upon and to the block or cylinder of an internal combustion engine of the type having poppet valves.

Another object is to provide a valve grinder forming a self-contained power unit and valve operating means.

10 Another object is to provide a unitary self-contained; motor-powered valve grinder, including means enabling a valve-engaging element thereof to be readily adjusted with respect to the position of the attached valve grinder to adapt the tool to various types of motors.

Another object is to provide means automatically acting to lift and shift the valve-engaging element of the tool so as to cause 20 a relative change of position of the valve on its seat during the grinding process.

Another object is to provide for the ready lifting of the valve-grinding element to entirely disengage it from the valve being 25 ground.

Another object is to provide in a self-contained, motor-powered valve grinder, means for automatically breaking the electric circuit supplying current to the motor 30 when the valve-engaging element is shifted to the clear position.

Other objects and advantages will be made manifest in the following specification of the embodiments of the invention illustrated in 35 the accompanying drawings, wherein:

Fig. 1 is a plan of the tool as applied to the head of a motor block.

Fig. 2 is a side elevation and partial section of the applied tool showing the valve-engaging element in effective valve-setting 40 and grinding position.

Fig. 3 is a section showing the motor switch parts in circuit closing relation.

Fig. 4 shows the motor switch parts in 45 circuit breaking position.

Fig. 5 is a side elevation and partial section showing the valve-engaging element in clearing position, and showing the tool column sustained in elevated position.

50 Fig. 6 is a section on line 6—6 of Fig. 2, showing the motor switch parts in detail.

Fig. 7 is an elevation and sectional view of the column.

55 Fig. 8 is a detailed sectional view of the spindle element reciprocating and rotating

means, and showing the spindle in lowered position.

Fig. 9 is an elevational view of parts shown in Fig. 8 and showing the spindle in repressed position.

60 Fig. 10 is a plan of a modified form of the column elevating means.

Fig. 11 is a side elevation showing the modified elevating means.

Fig. 12 is a section on line 12—12 of Fig. 11.

The present invention constitutes a valve grinding tool including a base 2 having a bifurcated foot portion 2^a which is adapted to be securely fastened as by a bolt B on a 70 plane-face F of an internal combustion engine having pocket valves V. In the utilization of the present tool, a temporary spring S is inserted under the valve V which is to be ground, and this valve is therefore, when 75 free, lifted off of its seat A.

The base 2 is provided with a post 3 and upon this there is turnably mounted a column 4 which is adapted to be shifted along the post end in a quick extending movement or 80 in a small adjusting movement to control the pressure of the valve V on its seat A. Therefore, means are provided for lifting the column 4 to its maximum degree with a quick action, and means are also provided 85 for making a fine adjustment of the column. Quick and maximum movement is given to the column so as to lift a spindle element 10 a considerable distance from the valve seat, and a smaller and fine adjustment is provided for so as to regulate the degree of pressure of the spindle 10 on the valve and therefore of the valve on the seat A.

90 One form of column adjusting means is shown as including a cam 7 which is turnably mounted on a fixed trunnion or pin 8 Fig. 6, forming a part of or attached to the base 2. This cam is clearly shown in Figs. 1 and 2, as provided with a lug 7^a through which is threaded an adjusting screw 9, one 100 end of which is engageable with a shoulder 2^b which may be formed as a part of the base 2. The effective face of the cam 7 is disposed toward the contiguous end of the column 4 and it will be seen that by turning the screw 9 it will cause a slight rotation of the cam about its axis or pin 8 with the result that the column will be elevated slightly the required degree. To effect a quick maximum elevation of the column 4 the screw 9 110

may be utilized as a lever so swing the cam from the position shown in Fig. 2 to the position shown in Fig. 5, with the result that the column 4 will be elevated to the maximum degree by the cam and thus sustain and hold the spindle 10 a considerable distance above the valve seat.

The spindle end is attached to or forms a part of a mechanism arranged in a gear-box 12 which is adapted to be swung in an arc on a pivotal support including a pin 13 in a block 14 which is detachably secured as by a screw 15 to the outer end of a substantial bracket arm 16. This arm is slidably supported in a guideway 4^a provided on or forming a part of the column 4; the arm 16 being disposed at a right-angle to the axis of the column 4. By this means it will be seen that the gear-box 12 has a swinging movement on the end of the arm 16 and that the arm can be radially extended from the column and thus provide for the ready adaptation and adjustment of the tool to various types of motors, this adjustment being further facilitated by the adjustment of the slotted base 2.

The sliding arm 16 may be provided with a rack edge 16^a engaging a pinion 17 disposed in the guideway 4^a and having a shaft 18 with an adjusting wheel 19, as clearly shown in Fig. 7.

To obtain a compact power equipment, the tool is provided preferably with an electric motor M mounted on the gear-box 12, and the motor shaft is provided with a pinion 20, Fig. 8, engaging a gear 21 having a shaft 22 journaled in the gear-box 12, and being provided with differentiated gears 23 and 24, which are keyed on the shaft.

The gear 23 is shown as meshing with a gear 25, while the gear 24 is shown as meshing with a gear 26 which is splined or otherwise slidably secured on the spindle 10 so as to provide for relative movement and drive the spindle.

As here shown, the gear 26 has a slotted hub 26^a through which passes a pin 26^b keying the gear to the spindle. In the present case the gear 25 is rotatably mounted on the hub-portion 26^a. These gears are rotative at different speeds by the gears 23-24.

It is desirable to provide a reciprocating movement to the spindle 10 while it is being rotated so that intermittently the spindle 10 will permit the valve V being ground to lift from its seat A and rotate with the spindle to take a new position when again pressed to its seat by the spindle so as to avoid scoring the valve and seat or either. This intermittent action of the spindle is permitted by means including a cam 27 provided on a side-face of a disc 27^a secured on the spindle 10. This cam is adapted to intermittently engage a reacting part of or on the gear 25 and which part is here shown as including a ball

28 sunk in an end-face of the gear 25. The spindle 10 and the cam 27 are yieldingly thrust in one direction as by a spring 30 disposed in the gear-box and reacting against the cam disc 27^a which in the present case is provided with a washer 31 to receive the spring-end.

Thus, after the spindle 10 has been aligned with the valve axis while the column 4 is elevated, then the elevating device is thrown over to lower the bracket arm and bring the spindle 10 down on to the valve V, and this will be forced to its seat against the action of the spring S. Following this the column is carefully adjusted by the screw 9 to bring the desired degree of pressure of the valve on its seat before, during or after which the motor M can be started so as to rotate the spindle. During the operation of the motor the gears 25 and 26 will be constantly driven with the result that the spindle is running and at the same time it is intermittently reciprocated as the cam 27 is engaged by the abutting part 28 rotated with and by the gear 25. As the cam engages the abutment 28 the spindle 10 is forced back against the spring 30 and the valve V is automatically lifted by the spring S. During the rotation of the gear 25 the abutment 28 will be disengaged from the cam 27 and the spindle will be again forced down and carry the valve to its seat.

When the valve is seated there will be a clearance between the cam 27 and its co-operating gear 26, thus insuring the positive seating of the valve.

In Figs. 10, 11 and 12, a somewhat modified form of elevating means is shown as including a cam 7^x turnable on a pivot 8^x as by means of a lever 9^x; the cam 7^x in its lowermost portion is limited by any suitable stop as a pin or shoulder 2^x.

A slightly modified form of means for close adjustment is shown in Fig. 11 as including a screw 9^a threaded in the head of a column 4 and engaging the top of a post 3.

It is desirable to provide means for automatically breaking the circuit supplying current to the motor end and to that end terminals T and T' Fig. 6 of the electric conductors are insulated in the base 2 and are attached to contact plates P and P', which are of quadrantal form in plane. Opposed to these plates is a substantially semi-circular plate or circuit closer C insulated from and mounted in a hub-portion of the cam 7. Thus, as the cam is swung to elevate the standard 4 the circuit-closing plate C shifts to break concurrent contact with the plates P-P', as in Fig. 4. When the cam 7 is swung to lower the column 4, then the circuit-closing plate C shifts over into concurrent end-engagement with the spaced contact plates P-P' and thus automatically closes the circuit to start and drive the mo-

tor when the valve-engaging spindle is in effective engaging position with the valve V.

Further embodiments, modifications and variations may be resorted to within the spirit of the invention.

What is claimed is:

1. A valve grinder comprising a support, a shaft mounted upon said support, two gears of different sizes mounted upon said shaft, a spindle parallel to said shaft, a gear rotatably mounted and meshing with one of the gears on said shaft, said gear being slidably keyed to said spindle, a second gear rotatable about the spindle and meshing with the other gear on said shaft, means providing a projection upon the second gear, a cam secured to the spindle adapted to be engaged by the projection to produce axial movement of the spindle, and means for rotating said shaft.

2. A valve grinder comprising a support, a shaft mounted upon said support, two gears of different sizes mounted upon said shaft, a spindle parallel to said shaft, a gear rotatably mounted and meshing with one of the gears on said shaft, said gear being slidably keyed to said spindle, a second gear rotatable about the spindle and meshing with the other gear on said shaft, means providing a projection upon the second gear, a cam secured to the spindle adapted to be engaged by the projection to produce axial movement of the spindle, means for rotating said shaft, and spring means for urging the spindle into a predetermined position.

3. A valve grinder comprising a support, a shaft rotatably mounted upon said support, means for rotating said shaft, a gear

rotatable upon the support having a projecting hub, a spindle slidably keyed to said gear, a second gear rotatable upon the hub, gear means upon the shaft for rotating said gears, a cam carried by the spindle, and means providing a projection upon the second gear adapted to engage the cam so as to produce axial sliding of the spindle.

4. A valve grinder comprising a support, a shaft rotatably mounted upon said support, means for rotating said shaft, a gear rotatable upon the support having a projecting hub, a spindle slidably keyed to said gear, a second gear rotatable upon the hub, gear means upon the shaft for rotating said gears, a cam carried by the spindle, means providing a projection upon the second gear adapted to engage the cam so as to produce axial sliding of the spindle, and spring means for urging the spindle into a predetermined position.

5. A valve grinder comprising a support, a shaft rotatably mounted upon said support, means for rotating said shaft, a gear rotatable upon the support having a projecting hub, a spindle slidably keyed to said gear, a second gear rotatable upon the hub, gear means upon the shaft for rotating said gears, a cam carried by the spindle, means providing a projection upon the second gear adapted to engage the cam so as to produce axial sliding of the spindle, and spring means for urging the spindle into a predetermined position, said spring means bearing upon said cam.

In testimony whereof I have signed my name to this specification.

ERWIN E. MILLER.
